DESIGN FOR AN AUTOMOBILE

Amos E. Northup, Detroit, Mich., assignor to The Murray Corporation of America, Detroit, Mich., a corporation of Delaware

Application November 2, 1935, Serial No. 59,342

Term of patent 7 years

To all whom it may concern:

Be it known that I, Amos E. Northup, a citizen of the United States, residing in Detroit, in the county of Wayne, State of Michigan, have invented a new, original, and ornamental Design for an Automobile, of which the following is a specification, reference being had to the accompanying drawing, forming a part thereof, wherein:

I claim:

The ornamental design for an automobile substantially as shown.

AMOS E. NORTHUP.
